(57) **CLAIM**

The ornamental design for a mobile computing device action pad, as shown and described.

DESCRIPTION

FIG. 1 is top perspective view depicting the mobile computing device action pad in a fully open desk mat or pad configuration with a mobile computing device positioned thereon, showing the claimed design.

FIG. 2 is a top perspective view depicting the mobile computing device action pad of FIG. 1 in the fully open desk mat or pad configuration.

FIG. 3 is a top perspective view depicting the mobile computing device action pad of FIG. 1 with the pair of built-in handles folded in and overlapping with the center desk mat or pad portion.

FIG. 4 is a top perspective view depicting the mobile computing device action pad of FIG. 1 in a closed folio configuration.

FIG. 5 is a top plan view depicting the mobile computing device action pad of FIG. 1 in the fully open desk mat or pad configuration.

FIG. 6 is a front side view depicting the mobile computing device action pad of FIG. 5.

FIG. 7 is a top plan view depicting the mobile computing device action pad of FIG. 1 in the closed folio configuration; and,

FIG. 8 is a right side view depicting the mobile computing device action pad of FIG. 7.

The mobile computing device illustrated in broken line represents environment. The remaining broken lines illustrate portions of the mobile computing device action pad. None of the broken lines form part of the claimed design.

1 Claim, 4 Drawing Sheets
